Patented Dec. 1, 1936

2,062,417

This is a continuation-in-part of my application for a patent for an improved closure, filed January 15, 1935, Serial No. 40,818, and for which a patent was issued on December 1, 1936, Serial No. 2,062,417.

This application is for an improved closure which is particularly adapted for use in connection with safety deposit boxes commonly used in banks and other institutions. It is an improvement in the device shown in my previous application, and it is an object of this invention to provide a closure which may be attached to doors, boxes or containers already in use or which, if so desired, may be built in or used as the front end of new structure, and which will prevent unauthorized access to the contents of the safety deposit box.

UNITED STATES PATENT OFFICE

2,062,417

CLOSURE

Allen E. Jay, Wilmington, Ohio

Application September 16, 1935, Serial No. 40,818

11 Claims. (CL 109—12)

This invention relates to an improved closure and is particularly adapted for use in connection with safety deposit boxes commonly used in banks and other institutions.

5 One object of the invention is to provide a closure which may be attached to doors, boxes or containers already in use or which, if so desired, may be built in or used as the front end of new structure, and which will prevent unauthorized access to the contents of the safety deposit box.

10 Another object of the invention is to provide a closure having a lock thereon which is adapted to be opened by means of a key to be carried by the device prior to sale and at all times to be in possession of the lessor of the safety deposit box so that officials of the institution having the box therein will be blameless in the event of loss of articles in the box.

15 Another object of the invention is to provide a closure for safety deposit boxes which will engage the walls adjacent the safety deposit box and will lock the box in closed position between the walls.

20 A further object of the invention is to provide a device of this character which, after unlocking, may be readily removed from the safety deposit box for permitting access to the box.

25 And a still further object of the invention is to provide a closure which may be manufactured cheaply and easily to sell at a nominal figure.

30 Other and incidental objects of the invention not specifically mentioned in the foregoing will render themselves apparent as the description of the invention proceeds.

35 My improved device is illustrated in the accompanying drawings wherein:

Figure 1 is a perspective view showing my improved closure as it would appear attached to a safety deposit box, the device being shown in open position, and the view being partly broken away and shown in section.

40 Figure 2 is an enlarged longitudinal horizontal sectional view showing my improved closure in position on a safety deposit box and showing the entire structure in closed position.

45 Figure 3 is an enlarged fragmentary sectional view on the line 3—3 of Figure 2, looking in the direction indicated by the arrows.

50 Figure 4 is an enlarged fragmentary detail sectional view showing the cam employed.

55 Figure 5 is a longitudinal horizontal sectional view showing a modified form of my invention.

Figure 6 is a longitudinal vertical sectional view of the modified form of the invention on the line 6—6 of Figure 5.

Referring now more particularly to the accompanying drawings, wherein like numerals of reference indicate like parts, the numeral 1 indicates a compartment which is of conventional construction and is provided with a swingingly mounted door 2 having a lock 3 thereon. It should be understood that the usual lock construction will be employed.

5 My improved closure comprises a frame section 4 which is provided with a bottom wall 5 and a top wall 6. An end wall 7 connects the walls 5 and 6 at one end. Connecting corresponding opposite ends of the walls at their edges is a web 8 which is projected medially of its height to form a hinge loop 9. Threaded through the wall 7 in vertical spaced relation are a pair of bolts 10 adapted to engage in recesses 11 in the side walls of the safety deposit box. Spring washers 101 may be used to retain the bolts under tension. The purpose for this will be set forth hereinafter. Formed on the top wall and extending throughout the major portion of its length medially thereof is an attaching flange 12 which is tapered toward its free end and is bent near its inner end to project downwardly substantially parallel with the web 8. The central portion of the flange 12 is struck out to define a retaining spring 13 which is adapted to frictionally engage the inner surface of the front wall of a safety deposit box. As best seen in Figure 1 of the drawings, the flange 12 is provided with an opening to receive a soft lead stud 14 which is adapted to carry the key to be used in locking the device. The key is shown at 15 and is preferably embedded in a coating or covering of relatively soft metal 16. The key will not be noticeable by the casual observer prior to sale of the device and it is thought that this feature will effectually eliminate many robberies which are caused by keys being removed from safety deposit boxes. After purchase, with suitable directions, the key may be removed from the stud 14 by shearing, tearing, or in any other manner. As the metal is soft, no trouble will be experienced in removing the key.

45 Swingingly connected with the frame section 4 is a door section 17 having upper and lower flanges 18 and 19 which are adapted to straddle the top and bottom walls 5 and 6 so that when the door section has been moved to closed position, the flanges 18 and 19 will overlie and underlie, respectively, the top and bottom walls 6 and 5. A completely closed device will be thus provided. The door section is adapted to terminate substantially flush with the end wall 7 and 55

carries a lock 20 having a keeper which, as shown in Figure 2, is adapted to engage behind a lip 21 formed on the wall 7 in locked position. Formed on the opposite end of the door section 17 are vertically spaced hinge loops 22 which are adapted to cooperate with the hinge loop 9 and a pin 23 for hingedly connecting the door section and frame section. The door 17 is projected between the hinge loops 22 and rolled at its 10 end to define a cam or wedging face 24.

Formed on the free edge of the top flange 18 of the door section, substantially medially thereof, and adapted to project inwardly over the top of a safety deposit box, is an offset locking lip 25.

15 A roller 26 is rotatably mounted in the cam face and said roller will permit more ready engagement of said cam with a surface, such as the interior of a compartment.

The bolts 10 are provided with coil springs 20 thereabout, as shown at 26, and these coil springs retain the bolts 10 under tension at all times and also permit ready adjustment of the bolts so that the device may be inserted in safety deposit box recesses of different sizes. A locking plate 27 is 25 carried by the bolts 10 and projects throughout the height of the wall 7, said locking plate being formed with flanges 28 engageable with the bolts for preventing accidental rotation thereof.

In use, when one of my closures is purchased 30 separately, the key is removed from the flange 12 and this flange is engaged over the front wall of a safety deposit box. The bolts 10 are simultaneously engaged in the sockets 11 and, of course, the door section 17 is swung to open position 35 during installation. The spring 13 will retain the frame section firmly in position on the front wall of the safety deposit box. The door 17 is then swung to closed position and, as best seen in Figures 3 and 4 of the drawings, as the door is 40 swung to closed position, the cam 24 and roller 26 will engage the inner surface of the wall of the compartment and will cooperate with the bolts 10 for binding the device in position. When the section is in closed position the locking lip 45 25 will overhang the top wall of the safety deposit box and will prevent access being gained thereto. After the door section has been swung to closed position the key may be inserted in the lock 20 and the keeper turned home behind the 50 lip 21. The outer door 2 may then be swung to closed position and the lock 3 locked so that a complete seal will be provided for the safety deposit box.

Referring now to the modification shown in 55 Figures 5 and 6 of the drawings, the compartment is designated at 30 and is provided with a door 31 and a lock 32 which may be of any desired construction. A safety deposit box is shown in dotted lines at 33 and this box will preferably 60 be of a construction identical with that of the preferred form.

A frame section is indicated in general by the numeral 34 and said frame section includes an end wall 35 which is bent laterally to define a stop or 65 jamb 36 at the front of the frame. The frame section also includes top and bottom walls 37 and 38 which are connected by integral webs 39 and 40. A rear plate 41 is secured to the webs 39 and 40 and is projected rearwardly and bent laterally 70 and then is bent downwardly to define an attaching flange 42. A portion of the flange 42 may be struck inwardly to define a retaining spring, as in the preferred form of the invention. The web 40 is formed with a reduced portion which is projected and rolled to define a hinge loop 43. The

rear plate 41 is formed at each end with a pair of vertically spaced lugs 44 which are, as shown in Figure 5, adapted to engage the forward wall of the safety deposit box and space the frame section therefrom. It will be understood that, as 5 in the preferred form, the frame section 34 is secured in position on the front wall of a safety deposit box by engagement of the attaching flange with said front wall.

Carried in the frame section 34 substantially 10 medially of its depth and near one end thereof, is a mounting plate 45 which is bent laterally at each end and riveted in place, as shown at 46. On the plate 45 at its inner portion is mounted a 15 guide 47.

I provide a latch member, which is indicated generally at 48, and this latch member has an inner U-shaped portion 49 which is formed with oppositely disposed rack teeth 50. Secured to the inner portion 49 at its inner end is a latch portion 51 including spaced parallel legs 52. The latch portion 51 is, as shown, offset with respect to the inner portion and is secured thereto by means of rivets, screws, or the like. The legs extend longitudinally of the frame section 34 and 20 are adapted to project through suitable openings in the wall 35. It should be noted that the inner portion 49 and the latch portion 51 may be formed of a single piece of material and said portions need not, necessarily, be offset in respect to each 25 other.

A bearing plate 53 is riveted or otherwise secured to the mounting plate 45 and is disposed between the legs of the inner portion 49. The bearing plate 53 is formed with an integral stub shaft or pin 54 which is adapted to receive a worm 55, the thread of which meshes with the teeth 50 of the inner portion 49.

Associated with the frame section 34 is a door section 56 which is swingingly connected to said 40 frame section by means of a hinge pin 57 which extends through the loop 43 and loops 58, formed on the door section 56. The door section has one end adapted to overlie the jamb 36, in closed position. A lock 59 is carried by the door section, 45 and the keeper thereof is adapted to engage behind said jamb 36. The opposite end of the door section is extended and rolled to form a cam 60 which carries a roller 61.

In use, the device is first placed in the box or 50 compartment 30. The worm 55 is then rotated for extending the ends of the legs 52 through the wall 35 into engagement with the wall of the box 30. If desired, openings to receive these ends 55 may be provided in the box. After the legs have been placed in proper position, the door section is closed, when the cam 60 and roller 61 will be engaged with the wall opposite that engaged by the legs for firmly clamping the device in place.

The device is characterized by the utmost simplicity in use and is fool-proof for the reason that it has few working parts and is very effective. It may be manufactured to sell to the trade at a low cost.

Having thus described the invention, what I 65 claim is:

1. In a closure, a frame section adapted to engage a wall of an article to be sealed, a door section swingingly connected therewith and having means overhanging the article to be sealed, and 70 means locking the door section and frame section as a unit for disposing the first mentioned means in overhanging relation to the article whereby said article will be effectually locked.

2. In a closure, a frame section having a flange 75

adapted to engage over a wall of a container to be sealed, said frame section having top and bottom walls and an end wall, a door section swingingly connected with the frame section and having flanges overhanging the top and bottom walls, one of said flanges having a lip adapted to project above the container for preventing access thereto, and a lock carried by the door section and having a keeper engageable with the end wall of the frame section for locking the two sections as a unit.

3. In a closure, a frame section having top and bottom walls, an end wall and a web, said top wall being projected and turned outwardly to define a flange adapted to engage behind a wall of a container for mounting the device thereon, bolts carried in the end wall and adapted to engage in recesses in a wall adjacent the container, a door section carried by the frame section and having upper and lower flanges, said upper flange being provided with a lip adapted in closed position to project above the lid of the container, said door section having a cam face at one end thereof adapted to engage the surface opposite the recesses for locking the device and container in position, and means carried by the door section for locking the door section in closed position on the frame section.

4. In a closure, a frame section having top and bottom walls, an end wall and a web provided with a hinge loop, a bolt carried by the end wall and adapted to engage in a recess, an attaching flange carried on the top wall and having a retaining spring, said flange being adapted to engage over a wall of a container to be locked, a door section swingingly connected with the frame section and having hinge loops adapted to cooperate with said first mentioned hinge loop, said door section having a lip adapted to overlie the lid of the container and having a cam adapted to cooperate with the bolt for locking the closure and the container in a compartment, said bolt being adjustable for adapting the device to compartments of various sizes, and a lock carried by the door section and adapted for engagement by a key for locking the frame section and door section in closed position.

5. A device of the class described including a frame section, means removably securing the frame section to a safety deposit box, a latch member carried by the frame section, said latch member including a latch portion having legs adapted to project into engagement with a wall of a compartment housing the safety deposit box, means controlling the latch member, and a door section connected with the frame section and having means for engaging a wall opposite that engaged by the latch portion and cooperating therewith for securing the device and deposit box within the compartment when the door section is in closed position.

6. A device of the class described including a frame section, an attaching flange for securing the frame section in position on a wall of a safety deposit box, a mounting plate carried by

the frame section, a latch member slideable on the mounting plate, said latch member including a latch portion having legs adapted to project into engagement with a wall of a compartment housing the safety deposit box, a worm carried by the mounting plate and engageable with the latch member for advancing the legs into engagement with said last mentioned wall, a door section carried by the frame section and having a cam engageable with the wall opposite the wall of the compartment for cooperating with the legs and securing the deposit box and device within the compartment when the door is in closed position, and a lock carried by the door and engageable with the frame section for retaining said door in closed position.

7. A device of the class described including a frame section, means for securing said frame section to a safety deposit box within a housing, means spacing the frame section from the deposit box, a latch member carried in the frame section, means removably engaging the latch member with a wall of the housing, and a door section hingedly connected to the frame section, said door section having a cam engageable with a wall opposite the first mentioned wall and cooperating with the legs for latching the device and deposit box within the housing when the door is in closed position.

8. A device of the class described including a frame section, a door section swingingly connected therewith and having means overhanging in locked position an article to be sealed, means for locking the door section and frame section as a unit for disposing the first mentioned means in overhanging relation to the article for locking said article, and a roller carried by the door section and cooperating therewith for securing the device in a compartment.

9. A device of the class described including a frame section, bolts carried by the frame section and being adapted for engagement with a wall of a compartment, a door section carried by the frame section and having a cam face, and a roller carried by the cam face, said cam face, roller and bolts cooperating to permit the wedging of the device in the compartment as the door is closed.

10. In a closure, a frame section, means carried by the frame section and adapted for engagement with a wall of a compartment, and a door section carried by the frame section and having a cam face, said cam face and said means cooperating to permit the wedging of the closure in the compartment as the door section is closed.

11. In a closure, a frame section, means carried thereby and adapted for engagement with a wall of a compartment, a door section carried by said frame section and having a cam face, and a roller carried by the cam face, said cam face, roller and means cooperating to permit the wedging of the closure in the compartment as the door section is shifted to closed position.

ALLEN E. JAY.
